ABSTRACT

An ornamental design for a telephone is disclosed in which the telephone is arcuate and includes a pushbutton dial that has a planar face and rectangular pushbuttons. The longitudinal walls on each side of the dial vary in height, the walls having a greater height at their ends than in the middle. In addition, the portion of the set between the dial and the mouthpiece end of the set includes a planar inclined ramp that extends at an angle to both the flat surface of the dial and the curved surface of the set.
